UNITED STATES PATENT OFFICE.

CHARLES E. BATES, OF CHESTER, PENNSYLVANIA.

ARMOR FOR PNEUMATIC TIRES.

1,270,482.

Specification of Letters Patent. Patented June 25, 1918.

Application filed December 4, 1916. Serial No. 134,873.

To all whom it may concern:

Be it known that I, CHARLES E. BATES, a citizen of the United States, residing at Chester, in the county of Delaware and 5 State of Pennsylvania, have invented certain new and useful Improvements in Armor for Pneumatic Tires, of which the following is a specification.

This invention relates to pneumatic tires 10 and more particularly to armors for this class of tires and particularly to an armored interliner and has for its object the production of a device of this class that will present at all times a metallic armored 15 surface.

Another object is to provide an interliner of this class that will present a smooth non-chafing face to the inner tube.

A still further object is to produce a device 20 of this class having an entirely new and novel form of armor that will be light and durable.

Other objects and advantages such as simplicity, durability, cheapness in manufacture 25 and the general improvement of the art will be fully brought out in the following specification and illustrated in the accompanying drawings in which:

Figure 1 is a top plan view of my device 30 partly broken away to show the different layers of construction,

Fig. 2 is a bottom plan view of a portion of my device,

Fig. 3 is a cross sectional view,

Fig. 4 is a perspective view of my device 35 as a whole.

Fig. 5 is a view showing the construction of the bottom row of disks.

Fig. 6 is a view of the special designed 40 rivet used in securing the two top layers of disks in place.

Referring more particularly to the drawings the numeral 1 designates the base of my interliner which is preferably leather. The 45 base 1 has a plurality of rows of flat disks 2 permanently secured to its surface. The disks 2 are spaced apart and in staggered relation to each other.

A plurality of rows of substantially star 50 shaped spaces 3 are left between the disks 2.

A plurality of other disks 4 slightly con-

cave, are mounted in the alternating rows of spaces 3, the disks 4 being of such size that their edges touch.

A still other plurality of disks 5 of the 55 same size and shape as the disks 4 are mounted in the remaining rows of spaces 3.

The disks 4 and 5 are loosely mounted on rivets 6 which have heads on both ends thus allowing flexibility. 60

A covering 7 is secured to the base 1 on the opposite side from the disks thus presenting a smooth non-chafing surface to the inner tube.

It will be readily seen that by my construction 65 the inner liner is clearly flexible and that the point of the base directly beneath the point where the edges of the disks 5 touch and the edges of the disks 4 touch is protected by the disks 2 which are flush 70 to and secured to the base 1.

It will also be apparent that the disks do not impair the flexibility as they are loosely mounted on the rivets 6 and do not destroy the flexibility of the flexible base, 75 and still present a solid or continuous metallic surface.

Having thus described my invention what I claim is:

1. An armored inner liner for pneumatic 80 tires comprising a base, a plurality of disks spaced apart and in staggered relation to each other rigidly secured to said base, other disks loosely mounted on rivets in said base between said first-mentioned disks, said second-named disks overlying said first-named disks, a third set of disks secured loosely 85 on rivets in said base between said second-named disks and extending over the spaces between said second-named disks, and means secured to the inner side of said base for preventing chafing of an inner tube. 90

2. An inner liner for pneumatic tires comprising a base of flexible material, a plurality of metallic disks rigidly secured to 95 said base in longitudinal rows, each of said rows being in staggered relation to the adjoining rows, thereby leaving longitudinal rows of substantially star-shaped spaces between said disks, a second plurality of metallic disks of greater size than said first-named disks and loosely mounted on rivets 100

secured in alternating rows of said spaces and adapted to overlie said first-named disks, a third plurality of disks of the same size as said second-named disks loosely mounted on rivets secured in the remaining rows of spaces and adapted to overlie said second-named disks, and a flexible cover member secured to the under side of said base to prevent chafing of an inner tube. In testimony whereof I hereto affix my 10 signature.

CHAS. E. BATES.
